WATER OR STEAM BOILER

George A. Tichbourne, Port Arthur, Ontario,
Canada

Application September 12, 1933, Serial No. 689,154

1 Claim. (Cl. 122—223)

The invention relates to improvements in low pressure water boilers and a general object of the invention is to provide a boiler having a relatively large water containing area exposed to the heat generated by the fire in the boiler and to obtain such area without unduly increasing the size of the boiler so that it will be cumbersome and unwieldy to install.

A further object of the invention is to provide a boiler wherein the combustion chamber and the fire pot are entirely water jacketed and a water jacketed smoke passage leads from the combustion chamber to the smoke outlet from the furnace.

15 A still further object is to provide a boiler having the last mentioned feature and wherein the water jacketed smoke passage is of a U-shape so that the hot products of combustion leaving the combustion chamber are given a relatively long travel before they leave the boiler in order that they may give up their heat to the water in the walls of the passage.

20 A further object of the invention is to provide a boiler having a water jacketed combustion chamber and fire pot and a relatively long water jacketed smoke passage communicating with the combustion chamber and water heating tubes located in both the combustion chamber and the smoke passage and in communication with the water in the jackets.

25 A further object is to provide a boiler formed from upstanding sections which can be readily butted and bolted together, the sections being so water jacketed that they provide when connected 30 a water jacketed fire pot and combustion chamber and a water jacketed relatively long smoke passage leading from the combustion chamber.

35 A still further object is to provide the several water jacketed sections each with exposed water tubes connected with the jackets and contained in the combustion chamber and the smoke passage when the sections are assembled.

40 With the above more important and other minor objects in view which will become more apparent as the description proceeds, the invention consists essentially in the arrangement and construction of parts hereinafter more particularly described, reference being had to the accompanying drawings, in which:

50 Fig. 1 is a side view of the furnace.

Fig. 2 is a plan view of the furnace.

Fig. 3 is a rear end view of the furnace.

Fig. 4 is a horizontal sectional view at 4—4

Figure 1.

55 Fig. 5 is a vertical cross sectional view at 5—5

Figure 2.

Fig. 6 is a vertical sectional view at 6—6

Figure 5.

Fig. 7 is a horizontal sectional view showing a

5 In the drawings like characters of reference indicate corresponding parts in the several figures.

10 The base 1 of the furnace is preferably made from cast iron and contains the ash pit 2 which is approached through the ash door 3 located at one end of the base. A suitable damper 4 is provided at the front of the base which can be opened or closed for draft purposes. The base supports in the usual manner the ends of the 15 grate bars 5, these overlying the ash pit and being pivotally mounted at their ends so that they can be shaken when desired. The grate bars are supplied with downwardly extending arms 6 and a number of the rear arms are connected 20 pivotally in the usual way to a forwardly extending shaker bar 7 connected to a forward lever 8 at the front of the furnace.

25 A number of the front arms are similarly connected to a shaker bar 9 which has its front end 20 attached to a lever 10.

30 The arrangement is such that when the lever 8 is operated forwardly and back, the rear grate bars are shaken and when the lever 10 is operated forwardly and back, the forward grate 25 bars are shaken. I have not given a detailed description of the latter grate bars as they are well known to those familiar with the art.

35 On the base 1, I mount the body 11 of the furnace which is somewhat narrower in width 30 than the base and has a rear portion extending rearwardly beyond the base and supported by suitable legs 12. In the principal views of the drawings, I have shown the body of the furnace as formed from two similar left and right up- 35 standing sections 13 and 14 having their inner sides butted together and provided in suitable locations with mating lugs 15 whereby the sections can be firmly fastened together by bolts 16. As the sections are identically constructed, 40 the description of one will suffice.

45 Each section is preferably made from boiler plates suitably shaped to supply the parts required and welded together to provide water tight joints. Actually each section presents a 45 water jacketed outer wall 17, water jacketed front and rear walls 18 and 19, a water jacketed top 20, two rearwardly disposed and spaced water legs 21 and 22, a further water leg 23 positioned more or less centrally above the grates and a bottom 50 leg 24 connecting the lower end of the leg 21 with the water jacket of the rear wall.

55 It will be observed that the outer ends of the legs 21, 22, 23 and 24 communicate directly with the water jacket of the outer wall 17 and that the upper end of the leg 22 communicates directly with the water jacket of the top 20 and further that the latter leg takes an intermediate position between the leg 21 and the rear wall 19 and has the lower end thereof spaced from the under- 60

lying leg 24 and that the leg 21 lies immediately to the rear of the base and actually forms the rear wall of the fire pot 25 and combustion chamber 26.

5 When the two sections are placed in position and bolted together, the ends 18 and 19 of the sections butt as do also the inner face of the legs 21, 22, 23 and 24 and there is no inter-communication between the sections, of the water in their 10 respective walls or legs.

The rear walls of the sections are provided with smoke outlet passages 27 and 28 which pass through the rear walls and the side wall of the section 14 is fitted with a fire door 29 opening to 15 the combustion chamber and with a clinker door 30 opening to the lower part of the fire pot in a location directly above the grates.

The top of each section is provided with a water outlet passage 31 and the passages communicate with a header 32 from which a common service pipe 33 passes. The outlets 27 and 28 are connected by a smoke pipe 34 and a smoke pipe 35 leads from the pipe 34 to the usual chimney flue. Each of the sections is also provided rearwardly 25 at the top with an inlet pipe 36 opening to the water jackets and the inlet pipes are connected by a header 37 with which a water return pipe 38 communicates.

In the rear water jacket of each section, I 30 form a vertical partition 39 which crosses the jacket and divides such jacket so that the incoming water has to flow first downwardly within the jacket.

When the two sections have been put in place, 35 it will be seen that the butting legs 23 centrally divide the fire pot so that either half or all the fire pot can be used for firing purposes as desired and that either half of the grate can be shaken by manipulating one or other of the levers 40 8 or 10. It will be also seen that the combustion chamber communicates over the top of the legs 21 with a U-shaped smoke passage 40 formed at the rear end of the furnace and communicating with the smoke outlets 27 and 28 and that 45 the walls of this U-shaped smoke passage are entirely water jacketed with the result that the heat of the passing products of combustion is utilized to advantage in heating the water in the walls of the passage.

50 Further it will be noticed that both the combustion chamber and the fire pot are enclosed within water jacketed walls and that the fire pot is divided by water jacketed legs.

In each section of the furnace, I locate three 55 sets of water tubes 41, 42 and 43 respectively, the tubes 41 crossing the combustion chamber and connecting the upper part of the leg 21 with the water jacketed front wall 18, the tubes 42 passing across the upper part of the combustion 60 chamber and down the smoke passage 40 and connecting the front part of the leg 24 with the water jacketed wall 18 and the tubes 43 extending downwardly within the rear part of the smoke passage 40 and connecting the rear part of the leg 24 with the upper part of the water leg 22.

The tubes are suitably spaced and alternated so that they can be readily approached for cleaning, repair or other purposes upon the sections of 70 the furnace being disjointed. It will be observed that the tubes in the upper part of the combustion chamber will be intensely heated and that

the tubes in the passage 40 will also be heated by the passing products of combustion. Suitable clean out doors 44 are provided so convenient access can be had to the bend in the passage 40 for cleaning, inspection or repair purposes.

A furnace constructed as described utilizes a maximum amount of heat created by the fire for water heating purposes due to the relatively large water heating exposure area provided and the various major parts are so arranged that they can be conveniently handled and installed and if necessary the sections can be readily taken apart for repair purposes. Further and as already mentioned, a fire can be built over the entire 10 grate area or either half of the grate can be used 15 when only a relatively small fire is required.

If it is desired to have a larger furnace, that is, one embodying more than two sections, such can be readily done by introducing one or more somewhat similar sections between the sections already described. In Figure 7, I have shown a furnace having the body thereof formed from three sections and in such a case, the base is made larger to accommodate the three sections. The side sections are made the same as those already described and the central section 45 is identical to the side sections with the exception that it has no water jacket corresponding to that shown at 17 and no leg corresponding to that shown at 23. It will of course be understood 20 that the centre section is supplied with the tubes the same as the side sections.

By so making the centre section, it is possible to add any number of sections 45 as they are simply put in place side by side between the sections 13 and 14 and then bolted together by the 30 bolts 16 passing through the lugs 15.

When such centre or intermediate sections are introduced, their outlet and inlet pipes are connected to the headers 32 and 37 and their smoke 40 outlets are connected to the pipe 34, it being understood of course at such time the pipes 32, 37 and 34 will be somewhat longer in order to accommodate the inserted section or sections.

In the principal views of the drawings, I have 45 shown the leg 23 adjacent the firing door with the top thereof terminating approximately at the level of the ledge of the doorway opening and the corresponding leg of the section remote from the door as rising well up within the combustion 50 chamber. This arrangement is resorted to so that there will be no interference with the firing of coal or fuel at the door.

What I claim as my invention is:—

A water boiler comprising a furnace body having water jacketed walls, vertical water legs crossing the rear part of the body and communicating with the water jacket the first of said water legs extending from the bottom of the furnace but stopping short of the top, and the second water leg extending from the top but stopping short of the bottom so as to form a water jacketed U-shaped smoke outlet passage between said water legs leading from the forepart of the body, horizontally disposed water heating tubes located in the upper forepart of the body, said water heating tubes being bent at right angles and extending vertically within the U-shaped smoke outlet passage, all of said tubes being in communication with the water in the jacket and the legs.

GEORGE A. TICHBOURNE.
